(57) **CLAIM**

The ornamental design for a container and a cap, as shown and described.

DESCRIPTION

FIG. 1 is a perspective view of a container and a cap, embodying our new design;

FIG. 2 is a front elevational view of the container and a cap of FIG. 1;

FIG. 3 is a back elevational view of the container and a cap of FIG. 1;

FIG. 4 is a right side elevational view of the container and a cap of FIG. 2;

FIG. 5 is a left side elevational view of the container and a cap of FIG. 2;

FIG. 6 is a top view of the container and the cap of FIG. 1; and,

FIG. 7 is a bottom view of the container and the cap of FIG. 1.
